UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN.

MACHINE OR CASTING-BOX FOR MAKING STEREOTYPE-PLATES.

No. 853,752.

Specification of Letters Patent.

Patented May 14, 1907.

Application filed July 18, 1906. Serial No. 326,764.

To all whom it may concern:

Be it known that I, HENRY F. BECHMAN, of Battle Creek, in the county of Calhoun and State of Michigan, have invented certain new and useful Improvements in Machines or Casting-Boxes for Making Stereotype-Plates; and I hereby declare that the following is a full, clear, and exact description thereof, reference being had to the accompanying drawings, which form part of this specification.

This invention is an improved machine or casting-box for making stereotype plates, for use on rotary cylinder printing presses, and the object of the invention is to make the drag or matrix holding portion of the box, movable from a vertical casting position to a horizontal position, so that while in the latter position the matrix can be readily placed in or removed therefrom, and the stereotype plates can be readily removed; the drag is so constructed that it will be practically balanced, and can be easily moved to either position; I further provide means whereby the movement of the drag to and from the cope causes it to automatically assume the proper positions; and also provide means whereby the drag may be securely locked to the cope during the casting operations, and can be released and partly started away from the cope after the casting operations are completed.

The invention will be fully understood from the following description and the accompanying drawings, in which—

Figure 1 is a plan view of the box closed, but showing the drag open in dotted lines. Fig. 2 is a side elevation of Fig. 1. Fig. 3 is a rear elevation of Fig. 2. Figs. 4 and 5 are details of the drag fastening devices; and Figs. 6 and 7 are detail views of the drag releasing devices. Fig. 8 is a detail view of the shaft.

Upon a suitable base 1 is mounted the cope 2, preferably in a vertical position, said cope being convex on its inner or casting-face, as usual, so as to give the desired contour to the inner side of the stereotype plates.

The drag, or matrix-holder 3 has a concave inner face, adapted to coincide with the convex face of cope 2, the opposed and meeting faces of the cope and drag being suitably formed, as usual, so that when closed to-

gether the space therebetween will form a mold for a curved stereotype plate as usual. Attached to the back of cope 2 are transverse bars 2^a secured by bolts 2^b the ends of 55 said bars projecting into the path of the side edges of flask 3, so as to stop the movement of the latter toward the cope at the exact mathematical point. The drag is provided with the usual hinged side guides 3^a on its 60 edges by which an ordinary matrix M can be held in position during the casting operation.

The drag 3 is provided with side-trunnions 3^b on which are rollers 3^c which are adapted 65 to run upon ways 1^b on the upper ends of side frames 1^a attached to base 1, so that the drag can be readily moved toward and from the fixed cope 2. The drag may be provided with handles 3^d to facilitate its movement by 70 the operator. The ways 1^b may be upturned at their rear ends 1^e to prevent the drag rolling off the ways by momentum. The drag is also provided with arms or brackets 3^e having rollers 3^f on their outer ends, which 75 rollers engage guide-slots 1^f in the side frames 1^a, the main portion of said slots being vertical, but their upper ends are bent horizontally inward toward the cope as at 1^g.

The construction of the parts is such that 80 when the drag is moved inward toward the cope rollers 3^f and slots 1^f cause the drag to assume a vertical position by the time roller 3^f reaches the part 1^g of slot 1^f, then the drag is kept perpendicular, parallel with the cope, 85 as it closes against the latter; and on the outward movement of the drag it first separates squarely and directly from the cope, and then is tilted over to a horizontal position, as indicated in dotted lines Figs. 1 and 2 and 90 95 remains in such position while the stereotype plate is removed, and the matrices arranged. The trunnions are so located that the drag is practically pivotally balanced thereon, so that very little effort is required to move the drag in or out, and it is automatically tilted to vertical or horizontal position by the arms 3^e and slots 1^f.

In order to fasten the drag securely against the cope during the casting operations, the 100 drag is provided, adjacent the trunnions, with studs 3^g, which are adapted to be en-

gaged by hooks 4^g, hung loosely on an eccentrically journaled rock-shaft 4, having eccentric journal portions 4^a by which it is supported in bearings 2^a attached to the rear or outer side of cope 2.

On the shaft adjacent the hooks are fixed collars 4^b to which are attached pins 4^c that are adapted to engage arc-shaped slots 4^d in the end of the hub of the adjacent hook (see Figs. 4 and 5) so that the shaft can be rocked somewhat without affecting the hooks 4^g. Thus the shaft 4 can be partly turned by hand-lever 4^x, starting from the position shown in Fig. 4, before the hook 4^g will be affected; but after pin 4^c reaches the rear end of slot 4^d the further backward movement of lever 4^x to the position shown in Fig. 5, will, through pin 4^c, cause hook 4^g to disengage stud 3^g. This rocking play of the shaft, independently of the hooks, enables me to use the shaft as a means for initially separating the drag from the cope, which is accomplished by friction rollers, or cams 4^f on the shaft adjacent the hooks; and when the shaft is rocked by moving lever 4^x to throw the hooks into engagement with the studs 3^g, the rollers 4^f will move away from, or clear of, the adjacent edges of the drag, (see Fig. 6) but as the lever 4^x is moved backward the rollers or cams 4^f are swung inward toward and into contact with the rear edges of the drag, at each side of the cope, and after the hooks 4^g disengage studs 3^g said rollers 4^f, on the continued rearward movement of lever 4^x, engage the edges of the drag and force it away from and clear of the cope (see Fig. 7) unlocking the box and enabling the operator to readily move the drag out to the position shown in dotted lines in Fig. 2.

Owing to the eccentric mounting of the shaft 4, after the hooks are closed a further downward and rearward pull on lever 4^x causes the hooks to draw the drag solidly and forcibly against the cope, and seal the flask tightly during the casting operations the slots 4^d being long enough to permit this movement before the pins 4^c reach the ends of the slots. The hooks 4^g drop onto pins 3^g by gravity as lever 4^x is swung rearward.

It will be seen that by reason of the balanced construction or mounting of the drag practically no exertion is required to move the drag from horizontal to vertical position; that the arms 3^e and slots 1^e effectively prevent the drag striking the cope while being tilted, or moved to or from the cope; and that the provision for a slight direct separating movement of the drag to and from the cope in finally closing or initially opening the box insures an accurate fitting of the matrix in the mold, and the proper clearance of the cast plate from the grooves in the cope.

Having described my invention what I

claim as new and desire to secure by Letters Patent is:

1. In a stereotype casting-box, the combination of a fixed cope, side frames beside the cope having horizontal ways on their upper ends, L-shaped guide-slots having their horizontal portions substantially parallel with the ways and extending toward the cope, a swinging drag provided with wheeled trunnions whereby it is supported on said guide-ways, and arms attached to the drag and engaging said slots whereby the drag is turned as it is moved on the ways, substantially as described.

2. In combination, a cope, and a drag movable to and from the cope; with an eccentrically mounted rock-shaft beside the cope, hook-arms loosely hung on said rock-shaft and adapted to engage the drag to lock the latter to the cope; collars on said shaft beside the hooks, and pin-and-slot-connections between the collars and hooks whereby the shaft is permitted a certain extent of movement without turning the hooks, substantially as described.

3. In a stereotype casting-box, the combination of a cope, a drag, a rock-shaft, hooks hung on said shaft adapted to engage and lock the drag to the cope, and eccentrics on said shaft adapted to force the drag away from the cope after the locking devices have released the drag, substantially as described.

4. In a stereotype casting-box, the combination of a cope, a drag, an eccentrically mounted rock-shaft attached to the cope, hooks hung on said shaft adapted to engage studs on the drag to lock the drag to the cope, and eccentric on said shaft adapted to move the drag away from the cope after the locking devices have disengaged the drag, substantially as described.

5. In a stereotype casting-box, the combination of a cope, a frame having horizontal ways and inverted L-shaped guide-slots below the ways having their horizontal portions substantially parallel with the ways and extending toward the cope, a drag having wheeled trunnions supporting it upon said ways, and arms provided with rollers connected to the drag, and engaging the guide-slots.

6. In a stereotype casting-box, the combination of a base, a cope fixed thereon, side frames provided with guide-ways and L-shaped guide-slots having their horizontal portions substantially parallel with the ways and extending toward the cope, a tiltable drag having trunnions whereby it is tiltably and movably mounted on and between said ways, and rearwardly projecting arms on said drag, and rollers on the rear ends of said arms engaging said guide-slots.

7. In combination, a cope, and a drag mov-

able to and from the cope; with an eccentrically mounted rock-shaft, hooks loosely hung on said rock-shaft and adapted to engage studs on the drag to lock the latter to the 5 cope, and connections between the hooks and shaft whereby the shaft is permitted a certain extent of movement without affecting the hooks, substantially as described.

In testimony that I claim the foregoing as my own, I affix my signature in presence of 10 two witnesses.

HENRY F. BECHMAN.

In presence of—

CHARLES A. GRAMES,
FRANK W. DUNNING.
